UNITED STATES PATENT OFFICE.

CHRISTOPHER C. MILES, OF WESTOVER, MARYLAND.

COMBINED STOVE AND TABLE.

1,224,773.

Specification of Letters Patent.

Patented May 1, 1917.

Application filed September 4, 1914. Serial No. 860,230.

To all whom it may concern:

Be it known that I, CHRISTOPHER C. MILES, a citizen of the United States, residing at Westover, in the county of Somerset and State of Maryland, have invented certain new and useful Improvements in Combined Stoves and Tables; and I do hereby declare the following to be a full, clear, and exact description of the invention, such as will enable others skilled in the art to which it appertains to make and use the same.

This invention relates to a combined stove and table and has for its object to provide a table having a hinged top and a heating apparatus arranged in spaced relation under the top for use as a cook stove.

Another object of the invention is the provision of a device of this character embodying a slideable drawer adapted to be withdrawn and swung downwardly in position to support the rear portion of the table.

With these and other objects in view, the invention consists in the novel construction, arrangement and the formation of parts, as will be hereinafter specifically described, claimed and illustrated in the accompanying drawing, in which,

Figure 1 represents a perspective view of the table, showing the top in open position, Fig. 2 represents a transverse sectional view therethrough,

Fig. 3 represents a longitudinal sectional view therethrough,

Fig. 4 represents a perspective view of the supporting bracket for the burner, and

Fig. 5 represents a perspective view, partly broken away, of the removable drawer.

Referring to the drawings in detail, wherein similar reference numerals designate corresponding parts throughout the several views, the numeral 6 indicates a pair of supporting legs for supporting the front portion of the table including the side boards 7 to which the upper ends of the legs are secured. A plate 8 having downwardly directed edges 9 is secured by rivets or the like to the inner faces of the side boards 7 in spaced relation to the top edges of the latter. A top 10 is hingedly secured at 11 to the rear side board 7 in which is slidably mounted a drawer 12^a. A drawer 12^b is slidably mounted beneath the plate 8 and is provided with a pair of angular arms 12^b secured to the rear member 12^c thereof and adapted to engage within suitable notches

formed on the inner face of the rear side board 7, when the drawer is pulled out and swung downwardly, to support the rear portion of the table in position, as clearly illustrated in Fig. 2. If desired, the drawer may be slid inwardly beneath the plate 8 for containing kitchen or other utensils, and in this position the rear portion of the table is supported upon a window sill, sink or other suitable support.

A heating drum 11 is removably positioned within an aperture formed centrally and adjacent the front edge of the plate 8 and is provided with an imperforate top 12 and an open lower end 13. A pipe 14 is positioned diametrically through the drum 11 below the plate 8 and is cutaway at its under portion within said drum to provide an opening 15. The pipe 14 extends longitudinally of the table and the opposite closed ends thereof are formed in their top portions with apertures in which are fitted the short pipes 16 communicating the pipe 14 with the chamber 17 between the plate 8 and the top or cover 10 of the table.

A bracket indicated generally by the numeral 17 is provided with an angularly directed end 18 secured in the front board 7 of the table and is provided with an offset portion 19, the lower extremity thereof being coiled as indicated at 20 in a horizontal plane to provide a support for a burner 21 projecting upwardly into the opened end 13 of the drum 11 and directly under the opening 15 of the pipe 14.

As illustrated in Fig. 1, the top 10 may be elevated and the burner 21 lighted to heat the plate 8 and top 12 of the drum 11 for cooking purposes. The heated air from the burner also passes through the pipe 14 and the short pipes 16 exhausting through the upper open ends of the latter. When desired, the top 10 of the table may be lowered, subsequently to extinguishing the burner 21 and the device used as a table.

What I claim is:

1. In combination, a body, supporting legs therefor, a plate secured in said body in spaced relation to the upper edges of the latter, said plate having a large central opening formed therein, a drum having an open bottom, a cover formed integral with said drum and crimped forming a horizontally disposed flange, said drum being secured in said central aperture and said

- flange overlying and engaging the upper edges of said plate, thereby supporting said drum, and a burner arranged in said drum to heat said cover.
- 5 2. In combination, a body, supporting legs therefor, a plate secured in said body in spaced relation to the upper edges of the latter, said plate having a large central opening formed therein, a drum having an
- 10 open bottom, a cover formed integral with said drum and crimped forming a horizontally disposed flange, a rod secured to said

body, said rod having a coiled offset end terminating below said drum forming a supporting bracket, and a removable burner 15 resting on said coiled offset end to heat said cover.

In testimony whereof I affix my signature in presence of two witnesses.

CHRISTOPHER C. MILES.
